CONTROL DEVICE

Victor N. Schubel, Dearborn, Mich.

Application November 9, 1946, Serial No. 709,074

3 Claims. (Cl. 192—8)

1

The present invention relates to a control device whereby a driven member is operable in response to a drive member, but otherwise is immobile.

One particular application of the present invention is noted for example as a control device to lock the rudder shaft of a small ship, such as a sailboat, at any given position. A driven shaft is operatively coupled to the boat's rudder which is held immobile against the action of wind, waves or water currents by the locking action of the control device embodying the present invention. A drive shaft is operatively coupled through the aforesaid control device to the boat's tiller and may be readily turned and set at any position, thereby operating the rudder shaft. Thus the forces of sudden gusts of wind, large waves or other factors which might cause the boat to lurch and which might otherwise jerk the tiller out of the hands of the helmsman, is prevented from being communicated from the rudder to the tiller.

Another application of the present control device is as a coupling for an automobile emergency hand brake wherein the hand lever is the drive member and the brake rod is the driven member. By virtue of the present invention the hand lever may be freely moved to various positions, and the brake will be set accordingly. Force applied to the brake rod cannot alter the brake setting and the brake will remain in its locked position until released by operation of the hand lever. Similarly, the device may be used for various steering or power controls or in other applications where the particular above mentioned characteristics are desired.

A primary object of the present invention is to provide a control device of the character described of improved and simplified construction which tends to eliminate play between the working parts involved and which holds a driven means immobile until released for movement in accordance with and under the control of a drive means, said control device being particularly adapted to provide for free operation of the drive means, and in turn the driven means, without jamming of the locking mechanism which prevents the driven means from moving independently of the drive means.

Further objects are to provide a control device of the character described having an improved rugged construction which reduces wear and deformation of the parts subject to stress and minimizes maintenance cost, the essential wearing parts being constructed of hardened steel

2

roller bearing races and hardened steel roller bearings, both of which are economically available for use with the present invention.

Other objects of this invention will appear in the following description and appended claims, reference being had to the accompanying drawings forming a part of this specification wherein like reference characters designate corresponding parts in the several views.

10 In the drawings:

Fig. 1 is a fragmentary vertical section through a control device embodying the present invention.

Fig. 2 is a section taken in the direction of the arrows essentially along the line 2—2 of Fig. 1.

Fig. 3 is an isometric exploded view showing the relationship between the various parts of the control device shown in Figs. 1 and 2.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

One embodiment of the present invention briefly proposes by way of example the use of a conventional circular roller bearing race, mounted stationarily to a frame, and one or more spaced rider members, which may be roller bearings, seated within and movable along the stationary or guide bearing race. A driven means, mounted for rotation about the center of the stationary bearing race, provides an extension or seat for each of said rider members. The application of forces on said driven means tending to rotate it independently of said riders will cause the extensions or rider seats of said driven means to press against said riders so as to press said riders against the sides of the stationary bearing race and thereby to immobilize said riders by friction with said stationary bearing race. Thus the rotation of the driven means is effectively blocked.

In order to effect rotation of the driven means, it is necessary to apply forces which will drive the riders along the stationary guide bearing race and simultaneously rotate the driven means so that the extensions or rider seats thereof will be unable to seat against and press against the riders. This latter is accomplished by the drive means which is adapted by rotation to press against the riders which are blocking rotation

of the driven means and to drive them along the stationary guide bearing race. Then, by forces communicated either from said riders to said driven means or from the drive means to said driven means, the driven means is rotated simultaneously with the riders.

The action discussed above will be clarified by reference to the drawings which show one particular embodiment of the present invention in a control device wherein the rotatable drive shaft 10 is supported within the collar 11, keyed for rotation therewith by means of the key 12 within the keyway 13, and held against endwise movement by the threaded set screw 14 which may be tightened against the base of the annular slot 14A of the shaft 10. A broad facing 15 of the collar 11 provides the arcuate drive means or lug 16 which has the roller bearing contacting faces 17 and 18. The outer surface of the drive lug 16 is concentric with the hardened stationary outer roller bearing guide race 19. The inner surface of the arcuate drive lug 16 is concentric with the hardened inner or driven bearing race 20, which latter is securely mounted on the eccentric extension 21 of the collar 22 to be rotatable therewith, Fig. 2. The collar 22 is concentrically mounted on the driven shaft 23 and is keyed to be rotatable therewith by the key 24 in the keyway 25. The threaded set screw 26 within the collar 22 is provided to be tightened against the base of the annular slot 26A so as to hold the driven shaft 23 from endwise movement. The eccentric projection 21 extends over the end of the drive shaft 10 and is rotatable thereabout, being spaced therefrom by the bearing 27. The thrust bearing 28 separates the coaxially aligned shafts 10 and 23.

It is to be noted that the inner bearing race 20 and outer bearing race 19 are eccentrically mounted one within the other to provide an eccentric space therebetween, and that the arcuate drive means 16 projects into the smaller portion of the aforesaid eccentric space, Fig. 2, so as to be disposed essentially symmetrically on either side of a plane passing through the axial centers of the two bearing races 19 and 20. Two movable riders 29 and 30, steel roller bearings in the present instance, are seated in contact with the two bearing races 19 and 20, within the eccentric space therebetween and adjacent the faces 17 and 18, respectively, of the drive lug 16 so as to partition said eccentric space essentially into an oversized and undersized portion relative to said roller bearings 29 and 30. Disposed within the oversized portion of said eccentric space between the bearing races 19 and 20 and between the two roller bearings 29 and 30 and secured to the driven bearing race 20 to be rotatable therewith is the tubular spring housing or rigid backing member 31 for the coil spring 32, the latter being adapted to press at its opposite ends against the riders or roller bearings 29 and 30 to urge said roller bearings 29 and 30 toward their respective seats and the undersized portion of the aforesaid eccentric space. The rigid backing member or tubular spring housing 31 is also essentially symmetrically disposed on either side of a plane through the axial centers of the bearing races 19 and 20 and is adjacent at its opposite ends to the roller bearings 29 and 30, being slightly spaced therefrom when the control device is at its rest position, Fig. 2.

In the structure shown it is preferred that the collar 11, the facing 15, and the arcuate drive means or lug 16 comprise portions of a one-piece structure which is rotatable with the drive shaft

10. Likewise, it is preferable that the eccentric extension 21 and the collar 22 are portions of a single structure which is rotatable with the driven shaft 23. Thus when forces are applied to the driven shaft 23 to rotate it in either direction independently of the drive shaft 10, the driven bearing race 20 which is eccentrically secured to the driven shaft 23 for rotation therewith bears against one or the other of the riders or roller bearings 29 or 30.

Force tending to rotate the driven shaft 23 in a clockwise direction, for example, will cause the driven bearing race 20 to press against the roller bearing 29. The force of the driven bearing race 20 against the bearing 29 may be resolved into two components, a vertical component tending to press the roller bearing 29 vertically against the stationary bearing guide race 19, and a tangential component tending to drive the roller bearing 29 along the stationary bearing guide race 19. Accordingly, it is only necessary to select the proper dimensions and disposition of the bearing races 19 and 20 and the roller bearing 29 so that the ratio of the tangential component of force to the vertical component of force will be less than the coefficient of friction between the bearing 29 and the stationary bearing guide race 19. In that event, pressure of the driven bearing race 20 on the roller bearing 29 will immobilize that roller bearing by friction with the stationary bearing guide race 19. Thus rotation of the driven bearing race 20 and, accordingly, the driven shaft 23 will be blocked. In a similar manner, counter-clockwise rotation of the shaft 23 will be prevented by the roller bearing 30.

When the drive shaft 10 is rotated clockwise, the face 17 of the drive means or lug 16 presses against the roller bearing 29 and readily drives it along the stationary bearing guide race 19. At the same time the face 18 is rotated away from the roller bearing 30. Furthermore, as soon as the roller bearing 29 traverses the slight increment which normally separates the roller bearing 29 from the rigid backing or spring housing 31, the force of the drive means 16 against the roller bearing 29 will be communicated to the rigid backing 31 and will, accordingly, drive the driven shaft 23. Similarly, counter-clockwise rotation of the drive shaft 10 will be communicated to the driven shaft 23 through the roller bearing 30.

It is preferred that the collar 11 be a bronze casting so as to provide a suitable bearing surface within the journal housing 33 in which the collar 11 is journaled. Likewise the collar 22 is preferably a bronze casting so as to provide a suitable bearing surface for the journal housing 34 in which the collar 22 is journaled. The facing 35 and annular extension 36 of the housing 34 provide a housing for the stationary bearing guide race 19 which latter tightly fits within the annular extension 36 and is thereby held stationary in its housing. The annular facing 37 of the housing 34 and the annular facing 38 of the housing 33 are drawn to each other by the plurality of bolts 39 within the threaded bolt holes 40 and bolt holes 41 in the facings 37 and 38 respectively.

The above described and other applications of the present control device are made feasible by the improved action and construction provided by the present invention. It is to be observed that in the operation of the present control device the locking action which prevents rotation 70 of the driven shaft 23 independently of the drive

shaft 10 does not depend in any sense upon driving the roller bearings 29 or 30 into a wedge, such as the wedge provided by the undersized portion of the eccentric space between the inner and outer bearing races 19 and 20. Consequently, the disadvantage of jamming which is frequently experienced with control devices employing a wedging action is avoided by the present invention. When torque is applied to rotate the driven shaft 23 independently of the drive shaft 10, the driven bearing race 20 merely bears against one or the other of the roller bearings 29 or 30 and is blocked against rotation. When the rotational torque is released, the pressure between the driven bearing race 20 and the roller bearing is simply relaxed and the roller bearing may be readily moved by operation of the drive shaft 10.

Another and primary consideration of the present invention is the high operating efficiency and economy of construction made possible by the use of hardened steel bearing races and hardened steel roller bearings which are economically produced in quantities by mass production methods. The principal mechanism of the control device shown is achieved merely by extracting all of the roller bearings except two from a conventional bearing assembly and by mounting the two bearing races eccentrically one within the other essentially as described.

In addition to the obvious economy over conventional methods of machining and hardening odd-shaped parts to make a control device of the class involved, the use of hardened steel bearing races and roller bearings reduces wear and deformation and provides a control device capable of resisting great stress without becoming faceted or deformed where the interacting parts press against each other. Where for the sake of economy, softer materials are used in place of the hardened bearing races and roller bearings employed in the present invention, the interacting parts become pocketed or flattened at various portions in the course of wear and frequent jamming of the locking mechanism results. Thus the present invention provides an economical solution to one of the major problems of conventional control devices and reduces the possibility of jamming of the locking mechanism to a minimum.

The economy and efficiency of a control device utilizing conventional hardened bearing races and roller bearings may be achieved by other embodiments of the spirit of my invention. For example, either the inner or outer bearing race could be adapted as a stationary bearing race secured to a housing. It is feasible to stationarily mount the inner bearing race concentrically with both the drive shaft 10 and driven shaft 23 and to couple the outer bearing race eccentrically to the driven shaft 23 to be rotatable therewith as a driven bearing race and to be rotatable eccentrically to the stationary inner bearing race. The function and operation of the remaining elements in such an embodiment remain the same. Torque tending to rotate the eccentric outer driven bearing race independently of the drive shaft 10 will press the roller bearings 29 or 30 as the case may be against the stationary inner race so as to block rotation of the driven shaft 23.

It is to be noted further that the ball bearing riders 29 and 30 as employed in the preferred embodiments shown in the drawings are not essential to the present invention and that other riders such as cylindrical roller bearings or slid-

able members that will seat between the bearing races and be movable along the stationary guide bearing race are feasible in other embodiments for specific purposes.

5 By the above disclosures and description I have provided important improvements in the economy and efficiency of a control device of the class described, which will not jam or wedge and which is particularly characterized by a simplified and 10 economical construction which provides for the use of conventional hardened steel bearing races and roller bearings for the principal operating mechanism.

I claim:

15 1. In combination, a stationary circular guide bearing race and a circular driven bearing race mounted eccentrically one within the other to provide an eccentric space therebetween, said driven bearing race being mounted for eccentric rotation about the center of said guide bearing race, two movable riders seated in contact with said two races and spaced apart within said eccentric space to partition said eccentric space essentially into an oversized and undersized portion 20 relative to said riders, a tubular spring housing disposed between said riders within the oversized portion of said eccentric space and secured to said driven bearing race and opening adjacent each of said riders, resilient means protruding 25 from the openings of said tubular spring housing to urge each of said riders toward its seat and the undersized portion of said eccentric space, said driven bearing race being adapted by eccentric rotation in either direction to rotate 30 against one of said riders and to immobilize that rider by friction contact with said stationary guide bearing race and thereby to prevent further rotation of said driven bearing race, drive means rotatable concentrically about the center 35 of said stationary guide bearing race, driving lugs provided by said drive means and positioned within the undersized portion of said eccentric space adjacent each of said riders to drive one or the other of said riders along said stationary guide bearing race upon rotation of said drive means 40 in either direction, motion of either of said riders against said adjacent tubular spring housing being communicated thereto to rotate said driven bearing race.

50 2. In combination, a rotatable driven means, a circular bearing race mounted eccentrically on said driven means for rotation therewith, a stationary circular guide bearing race mounted concentrically with said driven means, said driven bearing race and said guide bearing race being mounted eccentrically one within the other to provide an eccentric space therebetween, two movable riders seated within said eccentric space in contact with said two races and spaced apart 55 to partition said eccentric space essentially into an oversized and undersized portion relative to said riders, a rigid backing secured to said driven bearing race within the oversized portion of said eccentric space and adjacent each of said riders, resilient means to urge each of said riders toward its respective seat and the undersized portion of said eccentric space, said driven bearing race being thereby adapted by rotation in either direction to rotate against one of said riders and 60 to press that rider against said stationary guide bearing race and thereby to immobilize that rider by friction contact with said guide bearing race and thereby to prevent further rotation of said driven bearing race, and drive means rotatable 65 concentrically about the center of said stationary 70 bearing race and thereby to immobilize that rider by friction contact with said guide bearing race and thereby to prevent further rotation of said driven bearing race, and drive means rotatable concentrically about the center of said stationary

guide bearing race, two driving lugs provided by said drive means and rotatable therewith, one of said lugs being adjacent one of each of said riders and within the undersized portion of said eccentric space to drive one or the other of said riders upon rotation of said drive means in either direction, motion of either of said riders toward said adjacent rigid backing being communicated thereto to rotate said driven bearing race.

3. In a coupling to allow rotation of a driven shaft in response to rotation of a drive shaft and to lock said driven shaft against rotation otherwise, the combination of a circular bearing guide race and a circular driven bearing race mounted eccentrically one within the other to provide an eccentric space therebetween, said driven bearing race being mounted for eccentric rotation about the center of said guide race and being cooperative with said driven shaft to drive same, two movable riders seated in contact with said two races and spaced apart within said eccentric space to partition said eccentric space essentially into an oversized and undersized portion relative to said riders, a rigid backing disposed between

10

15

20

said riders within the oversized portion of said eccentric space and secured to said driven race, resilient means to urge each of said riders toward its seat and the undersized portion of said eccentric space, driving members cooperative with said drive shaft to be driven thereby and being adjacent each of said riders and within the undersized portion of said eccentric space.
